UNITED STATES PATENT OFFICE.

JOHN L. FERGUSON, OF JOLIET, ILLINOIS, ASSIGNOR TO THE QUAKER OATS COMPANY, OF CHICAGO, ILLINOIS, A CORPORATION OF NEW JERSEY.

CONVEYER.

1,423,095.

Specification of Letters Patent. Patented July 18, 1922.

Original application filed August 29, 1913, Serial No. 787,371. Divided and this application filed April 10, 1920. Serial No. 372,746.

To all whom it may concern:

Be it known that I, JOHN L. FERGUSON, a citizen of the United States, residing at Joliet, in the county of Will and State of Illinois, have invented new and useful Improvements in Conveyers, of which the following is a full, clear, concise, and exact description, reference being had to the accompanying drawing, forming a part of this specification.

My invention pertains to conveyers. It is particularly adaptable for carrying containers or other articles through suitable mechanism for operating thereon, as, for example, mechanism for closing or sealing containers of various types.

One of the objects of my invention is to provide a conveyer for work of the above and other character, which will require a minimum of floor space, and which will pass a large number of articles past a given point with great rapidity. I have shown in the accompanying drawings, and described in the following specification, a machine disclosing a form of my conveyer used in connection with a carton-sealing machine of that type wherein the flaps of the cartons are folded and sealed. It will be of course understood, however, that my conveyer may be used for numerous other purposes.

In the drawings—

Fig. 1 is a plan of a carton-sealing machine embodying my conveyer;

Fig. 2 is a side elevation of the same;

Fig. 3 is a sectional elevation of the same, the section being taken on the line 3—3 of Fig. 1 looking in the direction of the arrows; and

Fig. 4 is a section on the line 4—4 of Fig. 2 looking in the direction of the arrows.

Fig. 5 is diagrammatic view of the manner in which the cartons are handled after they are blown off into the chute.

In the embodiment of my invention illustrated in the accompanying drawings, I provide two endless conveyers, each of which is provided with means, in the particular embodiment illustrated, for carrying cartons, one series of said means being adapted to support carton shells with neither the

top nor bottom flaps folded, and the other a series of filled cartons with the top flaps unfolded. Both series of carton-supporting members or carriers traverse the same path during a portion of their travel; and the members are disposed on the conveyer so that the members of each series will be interspaced with those of the other series during the time when both series are traversing the same path. Therefore, the two endless conveyers with their associated carton-supporting members or carriers constitute a pair of horizontally disposed conveyer mechanisms, the paths of travel of said carriers coinciding as they travel under the folding and sealing mechanism.

Referring now to the drawings, the machine includes a bed 29 supported on suitable legs carrying bearings for a main drive shaft 30, which is driven from any suitable source of power. The shaft 30 is provided with a clutch 31 for throwing all of the parts of the machine, excepting certain parts 70 of the sealing apparatus, out of operation when desired, the clutch being adapted to be operated by means of a handle 32 placed in a position where it can be conveniently manipulated by the operator. The shaft 30 80 drives, through gearing 33, a countershaft 34, from which the majority of the parts of the machine receive their motion.

Mounted so as to rotate in vertical bearings carried by the bed 29 is a horizontal 85 sprocket wheel 35. The shaft of the sprocket wheel 35 also carries a gear wheel 36 which meshes with a pinion 37 carried by a stub shaft, which shaft is driven, through bevel gearing 38, by the countershaft 34. A 90 sprocket chain 39 passes around the sprocket wheel 35 and around a second sprocket wheel 40, which is supported at the opposite end of the machine to the wheel 35. The sprocket chain 39 carries the supporting 95 members for the carton shells.

The bed 29 carries a pair of rails 41 which enclose between them that part of the sprocket chain 39 which is located at the outside of the machine and at the ends thereof. The bed also carries a pair of rails 42 which enclose that part of the chain located down the center of the machine. As will hereinafter be explained, the rails 42

act in co-operation with the sprocket chain for the filled cartons as well as with the sprocket chain 39 which carries the supports for the empty cartons.

5 The supports for the empty cartons are spaced at equal distances along the sprocket chain 39. Each of these supports comprises a hollow stand 43 of a size such that a carton will fit thereover, and provided with an 10 inlet port at its lower end. The stand 43 is provided with a stop 45 upon which rests the edge of one of the side flaps of the carton, and is formed with a port 47, for permitting the carton to be blown off when air 15 under pressure is admitted through the inlet port. The stand 43 is formed with side flanges 48 which rest upon, and are slidably supported by, the rail 41 or the rail 42, according to the position of the stand in the 20 machine. It will be seen from the above that, as the sprocket chain 39 rotates, the stands 43 are carried first down the outside of the machine, and then down the center of the machine. As these stands pass down 25 the outside of the machine empty cartons are placed thereon by hand. As they pass down the center of the machine the cartons are operated upon by mechanism which is fully described in my co-pending application, Serial Number 787,371, filed August 29, 1913, and of which this application is a division. 30 By this mechanism the flaps of the carton are folded down and glued. After the folding and gluing operation, just prior to the 35 stands passing down the outside of the machine again, the cartons are blown off by air under pressure into suitable chutes which deliver them to a weighing and filling machine. The particular means whereby this 40 blow-off is accomplished is more clearly described and specifically claimed in my co-pending application, Serial No. 437,319, filed January 14, 1921.

In Fig. 5, however, I have shown diagrammatically the manner in which the cartons are handled after they are blown off into a chute 60; this apparatus being properly included with the present subject matter of this application which is directed to 45 the conveyer structure of my broader invention the present application being a divisional one, as above indicated. Although the chute 60 is shown as cut off at the top it should be understood that the same extends 50 into proximity with a weighing machine and a belt conveyer 70, the cartons being returned to the machine via said belt conveyer 70. Therefore, the cartons are automatically returned to the machine from the weighing 55 filling mechanism and fed one by one to the second conveyer, which again passes them beneath the same folding and gluing devices to seal the outer ends. It is apparent, therefore, that the blow-off and the chute where- 60 by the blown-off packages are carried from

the first conveyer to the belt 70 embodies means for transferring the cartons from the first conveyer to the second conveyer.

Describing now the second conveyer: Rotatably mounted on the bed 29 are a pair of 70 sprocket wheels 62 and 63, around which passes a sprocket chain 64. The shaft of the sprocket wheel 62 also carries a gear wheel 65 which meshes with the gear wheel 36 of the sprocket wheel 35. The chain 64 runs 75 down the center of the machine parallel with the chain 39, between the rails 42, and runs, at the outside of the machine and at the ends thereof, between rails 66, similar to rails 41. Secured to the chain 64, at spaces therealong 80 which are the same as the spaces between the stands 43, are a series of chairs 67 of such a height that they will support the filled cartons with their end flaps on the same plane as the end flaps of the empty cartons which 85 are carried by the stands 43. The chairs 67 are provided with backs 68 for supporting the cartons, and are formed with side flanges 69 which rest upon, and are slidably supported by, the rails 66 or the rails 42, according 90 to the position of the chairs in the machine. The chairs are so disposed upon the chain 64 that they will be interspaced at equal distances between the stands 43 during the time when the chairs and stands pass down 95 the center of the machine.

In order that the cartons may be held in place during the sealing operation, a pair of side members 103 are disposed down the center of the machine so as to slidably engage 100 the sides of the cartons adjacent the bottoms. A second pair of members 104 are provided for slidably engaging the sides of the cartons adjacent the tops.

While my conveyer has been described in 105 my co-pending application and shown in this application as used in connection with carton-sealing mechanism, it will be understood, of course, that while the conveyer is particularly advantageous in this connection, it can 110 be used in various ways without departing from the spirit of the invention as set forth in the appended claims.

Having thus described my invention, what I claim as new and desire to secure by Letters Patent, is:

1. A conveyer mechanism comprising a pair of endless conveyers, each having a series of supporting members, the supporting members of the conveyers being so disposed 120 that the members of one series will be interspaced with the members of the other series during a portion of their travel.

2. A conveyer mechanism including the two conveyers traveling throughout a portion of their length in separate paths and traveling together throughout a portion of their length, and means for transferring articles from the first conveyer to the second conveyer after said articles have traveled 130

- past the common portion of the paths on the first conveyer, whereby the articles will be caused to travel twice in the common path, once on the first conveyer and once on 5 the second conveyer.
3. A conveyer mechanism comprising a first conveyer, a second conveyer, and means for transferring articles from said first conveyer to said second conveyer, said second 10 conveyer carrying the articles during a part of their travel over the same path which they traveled when carried by the first conveyer.
4. A conveying mechanism comprising a 15 pair of horizontally disposed carrying devices whose paths of travel coincide as they pass a predetermined point.
5. A conveying mechanism comprising a 20 pair of horizontally disposed carrying devices having a portion of their paths of travel coinciding and a portion of their paths of travel separate and parallel.
6. A conveyer mechanism comprising a 25 pair of horizontally disposed endless conveyers, each having a series of supporting means of different type, the supporting means of the conveyers being so disposed that the members of each series will be interspaced during a portion of their travel.
- 30 7. A conveyer mechanism comprising a pair of horizontally disposed endless conveyers, each having a series of supporting means of different type, the paths of travel of said supporting means coinciding for a portion of their length, and the supporting means of the conveyers being so disposed that the members of each series will be interspaced during a portion of their travel.
8. A conveying mechanism comprising 40 two sets of horizontally disposed tracks converging into a single set, conveying members arranged to travel on said tracks, and means for advancing said members on the tracks.
- 45 9. A conveying mechanism comprising a pair of conveyers traveling throughout a portion of their length in separate paths and traveling together throughout a portion of their length.
- 50 10. A conveying mechanism comprising two sets of container carriers, means for causing said carriers to travel in separate paths during a portion of their travel and in the same path during a portion of their 55 travel.
11. A conveying mechanism comprising a conveyer provided with a series of conveying devices of one character and a second conveyer provided with a series of conveying 60 devices of another character, a portion of the paths of travel of said conveying devices of both series coinciding.
12. A conveyer mechanism comprising a conveyer provided with a plurality of stands for receiving empty containers and a second 65 conveyer provided with a plurality of chairs for receiving filled containers, a portion of the paths of travel of said stands and chairs coinciding.
13. A conveying mechanism comprising 70 two sets of horizontally disposed continuous tracks having a common section, receiving members arranged to travel on said tracks, and means for advancing said members along said tracks.
14. A conveying mechanism comprising 75 two sets of horizontally disposed continuous tracks having a common section disposed between two outer sections, receiving members arranged to travel on said tracks, and 80 means for advancing said members along said tracks.
15. A conveyer mechanism comprising 85 two sets of horizontal, substantially elliptical tracks having a common section, receiving members arranged to travel on said tracks, and means for advancing said members along said tracks.
16. A conveying mechanism comprising 90 two series of carrying devices having substantially elliptical paths of travel and whose paths of travel in a horizontal plane coincide for a portion of their length.
17. A conveyer mechanism comprising 95 two horizontal tracks having a common section, endless conveyer chains having their paths of travel adjacent said tracks, and carton advancing members connected to said chains and arranged to travel along said tracks.
18. In combination in a conveying mechanism comprising two loading areas and one operating area, two series of article-supporting means, means for conveying one series of said article-supporting means through 100 one loading area, and means for conveying the other series of said article-supporting means through the other loading area, said means operating to convey both series of article-supporting means through the operating area.
19. In combination in a conveying mechanism comprising two loading areas and one operating area, two series of article-supporting means, means for conveying one series 105 of said article-supporting means through one loading area, and means for conveying the other series of said article-supporting means through the other loading area, said means operating to convey both series of article-supporting means through the operating area.
- In witness whereof, I have hereunto subscribed my name.

JOHN L. FERGUSON.
